U.S. Appl. No. 29/596,921, filed Mar. 13, 2017. (Unpublished).

Primary Examiner — Wan Laymon*(74) Attorney, Agent, or Firm* — Saidman DesignLaw Group, LLC(57) **CLAIM**

The ornamental design for a pad for nerve stimulator device, as shown and described.

DESCRIPTION

FIG. 1 is a perspective view of a pad for nerve stimulator device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate structure or features which form no part of the claimed design.

1 Claim, 4 Drawing Sheets(56)
